UNITED STATES PATENT OFFICE.

EDWARD E. TALIAFERRO, OF COLORADO SPRINGS, COLORADO.

TYPE-BAR.

No. 925,852.

Specification of Letters Patent.

Patented June 22, 1909.

Application filed October 3, 1907. Serial No. 395,693.

To all whom it may concern:

Be it known that I, EDWARD E. TALIAFERRO, a citizen of the United States, and a resident of Colorado Springs, in the county of 5 El Paso and State of Colorado, have invented a new and Improved Type-Bar, of which the following is a full, clear, and exact description.

This invention relates to type bars and 10 more particularly to type bars used in connection with writing machines and the like.

An object of the invention is to provide a type bar for producing a plurality of original, 15 duplicate impressions by a single movement of the bar.

A further object of the invention is to provide a type bar for use in combination with a 20 plurality of platens and designed to produce duplicate impressions simultaneously at the platens.

A still further object of the invention is to provide a type bar designed to produce a plurality of duplicate, original impressions by a 25 single movement of the bar, and so arranged that all the impressions are made with equal force and distinctness.

The invention consists in the construction and combination of parts, to be more fully described hereinafter and particularly set 30 forth in the claims.

Reference is to be had to the accompanying drawings forming a part of this specification, in which similar characters of reference indicate corresponding parts in all the views, and 35 in which—

Figure 1 is a side elevation showing my type bar together with a pair of platens; Fig. 2 is a front elevation of the type bar; Fig. 3 is a rear elevation of the type bar; and 40 Fig. 4 is a transverse section on the line 4—4 of Fig. 1.

Before proceeding to a more detailed explanation of my invention, it should be stated that it is necessary to execute fully 45 per cent. of all writing produced by writing machines, in duplicate. By means of my type bar used in connection with suitably constructed writing machines, it is possible to write simultaneously two copies of equal 50 clearness and positive exactness, thus saving much time and entirely doing away with many inconveniences and possibilities of error where carbon paper or copy book devices are used. To accomplish this I employ 55 a single type bar having a movable section

which is provided with duplicate characters arranged to make simultaneous, duplicate impressions at platens provided for the purpose. The platens are mounted on a single carriage and are controlled in the usual manner, by means of suitable mechanism. Each platen, it will be understood, is provided with a sheet of paper upon which the impressions are made by the characters of the type bar. The construction of my type bar is 60 such that the impressions made upon the paper carried by the platens are of equal clearness, as the characters carried by the type bar are impressed with equal force against the platens. It will be understood 65 that by the word "duplicate" as applied to characters is meant similar characters; for instance, a capital "A" and a second or duplicate capital "A"; a small "a" and a second or duplicate "a". My type bar can also be 70 provided with duplicate sets of letters, and is then adapted for use in connection with type-writing machines and the like in which the type bar is shifted for the writing of certain 75 different characters. By a "duplicate" set 80 of characters is meant, for example, a capital "A" and a small "a", and a second or duplicate set comprising also a capital "A" and a small "a". If so desired, carbon copies can 85 also be executed at each platen, thereby increasing the number of copies produced.

A ribbon or other inking medium of common or preferred type, is to be used with my improved type bar where the same is employed in a machine of the usual construction. If necessary, a ribbon may be employed for each character or set of characters. 90

The construction of the type bar, aside from my improvements, may be of any common or preferred form or of any kind used in 95 writing machines. The operating mechanism, the means for mounting the type bar, and other details have no connection with my present invention.

Referring more particularly to the drawings, I provide a main type bar 1, which may be fashioned from any suitable material and may be of any form usually or most conveniently employed. The main bar 1, at the end remote from the keys, is laterally disposed and carries an offset, elongated head 2 preferably parallel to the adjacent body of the main bar. Near the center, the head 2 has a laterally extending ear 3, provided with an opening therethrough, in which is 110

located a pivot pin 4. A movable type bar section or member 5, is pivotally mounted upon the pin 4 by means of ears 6, provided with suitable openings for the purpose. The 5 section 5 is slotted and has the sides 7 arranged adjacent to the sides of the head 2. Near the ends the section 5 has parallel working faces 8, upon which are provided types or characters 9. The arrangement is 10 such that the faces of the types or characters are alined with each other and with the pivot pin 4.

The platens 10, which may be of any common or preferred form, are arranged adjacent 15 to the respective working faces of the type bar section 5; the latter, near each end, behind the working faces 8, has an integral yoke 11, which is arranged to engage the head 2 of the type bar and limit the working 20 movement of the movable section. The working faces are formed on blocks 12, which are secured in position between the sides of the movable sections by means of pins 13. The head 2 and the blocks 12 are suitably 25 beveled to permit the swinging movement of the movable member of the type bar.

As the character-carrying section of the type bar is movable pivotally with respect to the main type bar, the characters are projected with equal force against the respective platens; that is, the force applied to the type bar is equally distributed between the working faces of the movable type bar section, owing to the automatic adjustment of the 30 latter in striking against the platens. As the characters are alined with the pivotal point of the movable section, the characters will swing squarely against the platens at each impression, thereby obviating blurring 35 of the letters in writing, while permitting several degrees of play to allow for the automatic adjustment of the working faces.

Having thus described my invention I claim as new, and desire to secure by Letters 45 Patent:—

1. A type bar having a member pivoted thereon intermediate its ends, said member at each side of its pivotal point having a printing face, and back of each printing face 50 a stop adapted to engage the type bar to limit the swing of said member.
2. A type bar having a member pivoted thereon and free to swing to adjust itself in contacting with a plurality of platens, said 55 member having printing characters at each side of its pivotal point, and means for limiting the swing of said member, the pivotal point of said member lying substantially in the plane of said characters.
- 60 3. A type bar comprising a main bar having a section movable with respect thereto and provided with duplicate characters at each side of its connection with said main bar whereby said section can adjust itself 65 automatically in making duplicate impres-

sions at separated points, and means carried by said movable section for engagement with the main bar to limit the movement of said section.

4. A type bar, comprising a main bar, and 70 a section pivoted thereupon intermediate the ends of said section and having near the ends duplicate printing characters, said characters being alined with the pivotal point of said section, said section having a 75 limited freedom of movement to adjust itself automatically when contacting with a plurality of platens, the distance between said section and its connection with said main bar being less than the distance separating 80 said duplicate printing characters.

5. A type bar, comprising a main bar having a head, a section pivoted upon said head intermediate the ends thereof, and at the opposite extremities having working faces 85 provided with printing characters, means carried by said section and adapted to engage said head to limit the movement of said section, said head and said working faces at the adjacent sides being inclined and having 90 the inclined surfaces lying in planes passing through the pivotal center of said section.

6. A type bar, comprising a main bar having an elongated head, a section having spaced sides and pivoted upon said head, 95 whereby said sides are arranged at the sides of said head, said section near the ends having working faces provided with printing characters, said section further, at each end opposite the respective printing face, having a 100 yoke adapted to be positioned at the back of said head, whereby the movement of said section is limited, said head and said printing faces at the adjacent sides being radially inclined.

7. The combination, with a plurality of platens, of a type bar having a member pivoted thereon and free to swing to adjust itself in contacting with said platens, said member having printing characters at each side of its 110 pivotal point, and means for limiting the swing of said member.

8. The combination, with a plurality of platens, of a type bar comprising a main bar having a section movable with respect thereto and provided with duplicate characters at each side of its connection with said main bar whereby said section can adjust itself automatically in making duplicate impressions at said platens, and means for limiting the swing of said member.

9. A type bar comprising a main bar having an elongated head provided between its ends with a laterally extending ear, and a movable member provided with ears pivotally connected with said ear of the main bar, the said member being provided near its ends with printing characters located in alignment with the pivotal point of said member.

10. A type bar comprising a main bar hav-

ing an offset elongated head extending parallel to the body of the bar, the said head being provided at its center with a laterally extending ear, a movable slotted section having 5 its sides arranged adjacent to the sides of the head, the said section being provided with ears pivotally connected with the ear of said main bar, the said section having near its ends parallel working faces provided with 10 printing characters, the faces of the printing characters being alined with each other and with the pivot of said section.

11. A type bar comprising a main bar having an elongated head, provided with a projecting ear, a longitudinally slotted section provided with ears pivotally connected with the ear of the head, the said head extending in the space between the sides of said section, the said section being provided with yokes 15 extending at the back of the head and adapted to engage the head to limit the movement 20

of said section, the said section having working faces provided with printing characters.

12. A type bar comprising a section having spaced sides connected by yokes, blocks secured between the sides of said section at the ends thereof and provided with working faces having printing characters thereon, a main bar having an elongated head extending between the sides of said section, and a 25 pivotal connection between the head and the sides of the section intermediate the ends of the section, the said main bar being adapted to be engaged by the said yokes to limit the movement of said section.

In testimony whereof I have signed my name to this specification in the presence of two subscribing witnesses.

EDWARD E. TALIAFERRO.
